UNITED STATES PATENT OFFICE.

JACOB LEE WALZ, OF BALTIMORE, MARYLAND.

LINE-SPACING ATTACHMENT FOR TYPE-WRITERS.

1,189,642.

Specification of Letters Patent.

Patented July 4, 1916.

Application filed November 29, 1915. Serial No. 64,104.

To all whom it may concern:

Be it known that I, JACOB LEE WALZ, a citizen of the United States, residing at Baltimore, Maryland, have invented certain new and useful Improvements in Line-Spacing Attachments for Type-Writers, of which the following is a specification.

The present invention relates to improvements in attachments for typewriters and pertains more particularly to means for regulating the amount of circumferential movement of the platen according to the width of space it is desired to have between the lines of the work.

The principal object of the invention consists in providing mechanism which can be adjusted to regulate the width of the spaces between the lines of work and consists in constructing and attaching the parts so that the movement of the platen roll will be readily and accurately determined for any set adjustment.

A further object of the invention consists in providing an improved form of line spacer regulator in which practically all of the operating mechanism will be self contained within the cylindrical casing of the platen roller.

A still further object of the invention consists in providing a fine line adjustment gage, which will be so disposed in relation to the platen roller, that the index lines of the gage will lie directly adjacent the lines on the paper upon which the work is being done.

Other objects of the invention consist in providing additional means for easily releasing the line spacer regulator from the platen roll, when desired, and in providing means by which the platen roll can be readily manipulated independently of the line spacing mechanism.

With these and other objects in view, the invention consists in the combination and arrangement of parts more fully set forth in the following specification, illustrated in the accompanying drawings and more particularly pointed out in the appended claims.

In the drawings, Figure 1 is a plan view of a typewriter carriage frame and platen roll equipped with a line spacer mechanism according to one embodiment of the present invention. Fig. 2 is a horizontal longitudinal section through the platen roll showing the line spacer operating mechanism contained therein. Fig. 3 is a vertical longitudinal

section through the platen roll with parts shown in elevation. Fig. 4 is a side elevation, and Fig. 5 is a front elevation of a detail of one of the inner clutch members. Fig. 6 is a front elevation and Fig. 7 is a side elevation of another detail of the other inner clutch member. Fig. 8 is a detail of an operating segment detached. Fig. 9 is a horizontal longitudinal section of a modified form of the invention with parts shown in elevation. Fig. 10 is a transverse section on line 10—10 of Fig. 9. Fig. 11 is a fragmentary detail of a part of the mechanism shown in Fig. 9 seen in front elevation. Figs. 12, 12^a and 12^b are top plan views and right and left end views respectively of the skeleton block shown in Figs. 2 and 3. Fig. 13 is a detail of a supplemental paper gage. Figs. 14 and 15 are details. Figs. 16 and 17 are detail views of the modification shown in Fig. 9. Fig. 18 is a sectional detail plan view of a further modification.

Referring to the drawings the usual carriage frame 1 is shown in Fig. 1, in which the ends of the platen roll P are carried. In the majority of cases it has been customary to provide the platen roller with end spindles and arrange the line spacing mechanism at one end so as to partially rotate the platen roller about its spindles each time the work is to be advanced. In the present invention a stationary inner cylindrical shell or casing is non-rotatably mounted in the ends of the carriage frame. The platen roller is in the form of a second cylindrical casing or shell adapted to fit over the inner stationary shell and mechanism is provided to alternately lock the outer roller with the inner shell and to move the outer one circumferentially in relation thereto. Suitable clutch mechanism and timing devices for effecting these movements of the parts are provided within the inner fixed shell.

The inner cylindrical casing comprises a metallic shell 2, shown at the left, inside of the frame 1 (see Fig. 2) and this shell 2 extends within the outer platen roller P for a distance about three-quarters of the length of the latter. At its left hand end the shell 2 is fastened by means of screws 2^a to a block 3 having a squared extension 4, fitting a correspondingly shaped opening in the frame 1. The block 3 and its extension 4 are provided with a central bore forming the end bearing 105 for a rod or shaft 5, which carries at its extreme outer end a knurled finger wheel, this

last member having index mechanism attached to it as will be hereinafter described. The inner end of the shaft 5 finds a sliding bearing in a tubular sleeve 7, which in turn has a loose bearing in the central bore of a second block 3^a to which the cylindrical shell 2 is fixed by means of screws 2^b in a manner similar to its end connection with the block 3. The tubular sleeve 7 extends slightly beyond its bearing in the block 3^a and has pinned to its end a disk-shaped block 8. The shaft 5 has small rectangular pins 9, 9' projecting therefrom adapted to extend into oblong slots 10 in the sleeve 7 to permit a sliding movement of the latter in relation to the former. The inner pin 9' is formed with a circular band or collar 11 fixed thereto and adapted to encircle the sleeve 7 on which it slides. At one side the block 3^a is provided with an annular extension 3^x having an in-turned annular flange extending therefrom, as shown at 3^c. A guide block 12 having a cylindrical hub portion 12^a, extending along the sleeve 7 and pinned thereto, is provided and so positioned on the sleeve as to form a proper stop to limit the inward movement of the collar 11 carried by pin 9' from shaft 5. The sleeve 7 is formed at its opposite end with a small upturned flange 7^a. A coiled spring 13 surrounds the portion of the sleeve 7 extending between the end flange 7^a and the encircling collar 11 above referred to. A second guiding block 14 (see Fig. 14) somewhat similar to the first mentioned block 12, but provided with transverse roller 14^a extending across the upper and lower arms of the H-shaped portions, is pinned directly to the shaft 5 at a suitable point along its length. A pair of inclined fingers 15 are supported in the two guide blocks 12 and 14 respectively. They are each formed at their inner extremities with notched ends 15^a adapted to engage with the inturned annular flange 3^c of the block 3^a. At the opposite ends the fingers 15 are formed with inwardly curved portions 15^b guided along the inner sides of the roller pins 14^a. With the parts in the position shown in Fig. 2, the inclined fingers 15 frictionally engage by means of their notched ends 15^a, the flange 3^c of block 3^a and hence there can be no rotation of the shaft 5 or the disk 8 carried at the extreme right hand end of the sleeve 7. The inclined fingers 15 have a fulcrum bearing along the hub portion of the guide block 12. A pair of spring pressed pivoted fingers 16^a are carried on the disk 8 and are intended to coöperate with parts of a clutch and timing mechanism hereinafter to be described. The position however, of these fingers is set through the operation of the mechanism just described and it is accomplished by imparting to the block or disk 8 a partial rotation. The rotation of disk 8 is attained by manipulating the knurled

finger wheel 6. Before the wheel 6 can be turned it is first necessary to draw the shaft 5 in the direction of the arrow *a* indicated in Fig. 2. This is done by pulling the knurled finger wheel 6 away from the carriage frame. As the shaft 5 moves it carries with it the guide block 14 and as the roller pins 14^a pass down the curved ends 15^b of the fingers 15 the latter are loosened and their inner ends 15^a released from frictional engagement with the flange 3^c of block 3^a. The shaft 5 can now be turned in its bearing and because of the pin and slot connection with it the sleeve 7 will also be turned, carrying the block 8. As soon as the knurled finger wheel 6 is released the shaft 5 will be drawn inwardly in a direction opposite to that shown by the arrow in Fig. 2, by means of the coiled spring 13 which was previously compressed between the flange 7^a and collar 11. The parts will again assume their normal position with the fingers 15 locked to the block 3^a.

Considering the mechanism incased within the right hand end of the platen roller and controlled by the operating device at the right side of the carriage frame 1, it will be seen that the construction and arrangement of these parts is such as will enable them to coöperate readily with the several parts already described.

A central shaft or rod 16 is provided, having a bearing at its inner end in the end of the tubular sleeve 7 above referred to. Near its outer end the shaft 16 is formed with a squared portion 16^a passing through a circular bushing 17 in the carriage frame 1. A knurled finger wheel 18 is non-rotatably carried on the end of the shaft 16 projecting beyond the frame 1 and being retained in place by a threaded nut 19. Just inside the frame 1 a slotted segment 20 (see Fig. 8) is carried on the squared portion 16^a of the rod 16 having an integral arm 20^a with a squared opening therein corresponding exactly in size and shape with the squared shaft portion 16^a. An end ring 21 is supported from the shaft 16 by a centrally perforated plate 21^a and has formed thereon an ear 21^b with a pin 22 extending therefrom adapted to engage in the slotted portion of segment 20. At its inner side the ring 21 is formed with an in-turned flange 21^c, the purpose of which will be hereinafter described.

Near the inner end of the shaft 16 a disk-shaped member 23 is pinned thereon and is provided with a transverse bar 24 secured to its left side terminating in a pair of oppositely extending teeth 25. (See Figs. 6 and 7.) This member, which is hereinafter referred to as the fixed clutch member, abuts against the face of the block 8 on the end of sleeve 7. Adjacent to the teeth 25 and fastened at opposite points around the cir-

circumference of the fixed clutch members 23 by means of screws are a pair of outwardly flaring pointed teeth 26, 26. Loosely mounted on the shaft 16 and held normally in contact with the right hand face of the fixed clutch member 23 is a movable clutch member 27 comprising a cylindrical portion having a tubular extension 28 integral therewith. Pivoted mounted on diametrically opposite flattened portions of the movable clutch member 27 (see Fig. 5) are a pair of members 29 comprising teeth 30 adapted to extend beyond one face of the cylindrical portion of member 27 in the path of the teeth 26 and also provided with upturned tail pieces 31 extending beyond the opposite face of the cylindrical portion 27 in position to contact with stop members 32', herein-after to be referred to. The normal position of the pivoted members 29 is maintained by means of pins 32, and springs 33 clearly shown in Figs. 4 and 5. Adjacent to the movable clutch member 27 is a cylindrical block 34 supported at its center on the shaft 16 and having feathered key connection at its circumference with the fixed cylindrical casing 2. The tubular extension 28 of the movable clutch member 27 is provided with a pair of exterior helical ribs 28^a and the adjacent face of the block 34 is formed with a correspondingly shaped recess having interior helical grooves in which the ribs 28^a are adapted to engage. The block 34 is provided at one side with a cup-shaped flange 35 and at its other side with an annular flange 36 and recess 37. The stop pins 32' project from one side of the block 34 in position to be engaged by the tail pieces 31 of the members 29 on movable clutch 27.

A tubular sleeve 38 is rigidly carried at the right hand side of block 34 and extends therefrom concentrically disposed about the shaft 16. The sleeve 38 has a sliding bearing with a central hub portion 39 of a skeleton block member 40. This skeleton block 40 is of a general cylindrical conformation having an enlarged head portion 41 at its right hand end and fastened by screws to the outer cylindrical casing which carries the platen roller. The block is formed with slots 40^a and 40^b running longitudinally throughout its length and bisecting each other along the central axis of the block.

Two squared hub portions 42 and 39 respectively, spaced apart are provided, being centrally bored for the passage of the shaft 16 therethrough. A coiled spring 43 encircles a portion of the shaft 16, having one end bearing against the right hand end of the tubular sleeve extension 38 and the opposite end bearing against the inner end of the squared hub portion 42 of block 40.

A pair of levers 44 are mounted in the horizontal slot having their ends fulcrumed on

the squared hub portion 42 and formed with recessed end members 44^a adapted to engage the depending flange 21^c of ring 21. The opposite ends of the levers 44 are tapered as shown at 44^b and are adapted to be acted upon by a cam block 45 pinned to the sleeve 38 and sliding therewith in the horizontal slot of the skeleton block 40. A second pair of levers 46 are mounted in the vertical slots of the block 40 having notched end portions engaging the inturned flange 36 of block 34. These levers are fulcrumed at 47 to small flat projecting lips 48 of the block 40. At their opposite ends the levers 46 are formed with outwardly curved extremities adapted to contact against small roller pins 49 carried in small blocks set across the vertical slot of the block 40.

A coiled spring 50 encircles the sleeve or hub of the finger wheel 18, having one of its ends fixed in the carriage frame 1 and its other clamped around a projection or lug 50^a on the sleeve. The purpose of this spring is to return the parts to normal position as soon as the finger wheel 18 has been turned and released. A pivoted catch or detent 51 is carried on the end of frame 1 adapted to engage when in operative position, the top of lug 50^a to hold the wheel 18 and shaft 16 against rotation when the several clutch members with the cylindrical casing are in neutral position. When such is the case, the platen roller P can be turned freely forward or backward by means of a small knurled finger wheel 52 mounted on a stub shaft 53 located in a supplemental frame at the rear and at one side of the carriage frame. The shaft 53 has a slight sliding movement in its bearings and carries near its inner end a conical friction member 54 adapted to mesh with a similar friction conical member 55, carried on an idler shaft 56 on which is also non-rotatably carried a friction driving roller 57, having contact with the outer surface of the platen roll P. A small leaf spring 58 tends to keep the shaft 53 in a fixed position with the member 54 normally inoperative or away from contact with the member 55. When it is desired to turn the platen roll by means of the knurled finger wheel 52, the shaft is pulled outwardly in the direction of the arrow and temporarily fixed in that position by means of a pivoted catch 59, which engages a slot 60 on the shaft 53. Any turning of finger wheel 52 will be directly transmitted to the platen roll P.

The knurled finger wheel 6 has extending therefrom a finger or pointer 61 adapted to be moved across a line gage 62 lying just above the platen roller P and conforming to the curvature of its surface. A supplemental line gage 63 is attached to one of the usual spring clips 64 by which the paper is held against the platen roll.

The operation of the device is as follows: When it is desired to set the mechanism so as to advance the work paper, a given number of line spaces, or a given portion of a line space, the amount of throw which it is intended to give the platen roll P is set by pulling the knurled wheel 6 out in the direction of the arrow and turning it until the pointer 61 has registered with the proper index number on the gage piece 62. What actually takes place when this is done is the adjustment of fingers 16' on block 8 circumferentially in relation to the teeth 25 carried on the inner clutch member 23. The result is obtained by moving shaft 5 in the direction of the arrow α , Fig. 2 carrying with it the guide block 14 releasing the fingers 15; so as to permit the turning or partial rotation of shaft 5, sleeve 7 and block 8 carried thereon. After the degree of movement of the line spacer has once been set it is only necessary to turn the knob or finger wheel 18 until the platen roll has been advanced the predetermined amount and release the finger wheel whereupon the parts will be quickly and automatically returned to position. The cycle of operations which is attendant upon the partial rotation of shaft 16 through wheel 18 is briefly; the movement of shaft 16 causes clutch member 23 to rotate in the direction of the arrow (Fig. 6) and through the engagement of its teeth 26 with the teeth 30 of the pivoted members 29 results in a corresponding movement of the clutch member 27. As 23 and 27 rotate in unison the block 34 is displaced longitudinally due to the helical worm thread 28. As the block 34 moves to the right the sleeve 38 carrying guide block 45 also moves in the same direction, the skeleton block does not move with the result that lever fingers 44 are clamped to ring 21 and fingers 46 are released from flange 36. At this time the slotted segment 20 engages pin 22 and turns ring 21, which in turn has the platen roller clamped to it by the fingers 44. As soon as the tail pieces 31 of the member 29 come in contact with stop 32', the teeth 30 and teeth 26 become disengaged whereupon clutch member 27 ceases to rotate but the other clutch member 23 continues its movement until the teeth 25 have passed through a slot in the first finger 16' and have engaged a portion of the second finger 16' with which they coöperate to swing the said finger 16 out of engagement with the collar 35 of block 34. The instant this occurs springs 43 and 50 restore the parts to normal position and the operation may be repeated as many times as desired, without changing the line spacing adjustment at the end.

Before the co-acting clutch members 23 and 27 have been moved sufficiently to have effected any tripping action of the several fingers carried thereon and while the block

34 and sleeve 38 have moved only far enough to cause the fingers 44 and 46 to be in their clamped relation to the respective fingers with which they engage,—when the parts are in this so-called neutral position, if the γ 70 detent 51 is thrown over the lug 50, then the wheel 18 becomes temporarily fixed against rotation, and the platen roller can be easily moved in either direction by manipulation of knurled wheel 52.

Instead of having a finger wheel 6 at the outer end of shaft 5 so arranged that the two must be pulled outwardly and then turned in order to set the adjustment of the inner clutch members, an arrangement is provided γ 75 by which the same result may be obtained by simply turning two members in unison without the necessity of the outward pulling action before described. In Fig. 18 an arrangement is illustrated by which the inner γ 80 clutch members can be properly adjusted by turning two members located at the left hand end of the platen roller. As here shown the rod 5' performs the same functions as rod 5, shown in the form illustrated γ 85 in Fig. 2, but it is operated in a different manner. At its outer end an upright arm 17' is pinned thereto and carries at its upper end a line marker 18' extending across to move over the line index plate. An extension 20' on arm 17' provides a suitable finger hold for rotating the member 17'. A sleeve 6' fits over the shaft 5' and has keyed thereon a finger wheel 7' by which it is adapted to be turned. A worm thread 8' γ 90 is provided on the outer surface of the sleeve 6' and is adapted to be engaged by an interiorly formed thread in a block 3' fixed to the frame. Flat lateral extensions 9', 9' are attached to block 3' and form guides for γ 95 a block 14'', which is adapted to slide laterally on shaft 5'. The block 14'' is constructed in a similar manner and performs the same functions as block 14, shown in Fig. 1. Rollers 14 α are carried thereon to γ 100 press on the inclined fingers 15''. The block 14'' is moved by two small projections 19' at the end of sleeve 6'. A coiled spring 13' similar to that in Fig. 1 is provided, having one end bearing against block 14'' and the γ 105 other against a block 12' corresponding to block 12 of the other form.

It will be seen that the amount of circumferential displacement of the platen roller is determined by turning the member 17' by γ 110 finger piece 20' until extension 18 has registered with the proper marking on the line spacing index; thus block 12' with its parts will be properly set, then finger wheel 7' is turned moving sleeve 6', advancing it to the γ 115 right by reason of the worm thread 8' in fixed block 3'. This results in guide block 14'' moving to the right and locking through the fingers 15'', the parts exactly as is done when fingers 15 of Fig. 1 are compressed. γ 120 γ 125 γ 130

Fig. 9 shows a modified form of the invention in which all the operating devices are arranged at one side of the carriage frame. Here many of the parts are identical with those already described and to avoid repetition they will not be described in detail.

A central shaft 65 carrying on its end a knurled finger wheel 66 is mounted in the frame and extends into the cylindrical casting from the right hand end. At its inner end, the shaft 65 carries a guide block 14' operating fingers 15' similar in construction and operation to the parts 14 and 15, formerly described. A sleeve member 67 surrounds the shaft 66 and the shaft 16 of the principal form carrying a similar clutch member at its inner end. Fixed to the outer end of sleeve 67 is a worm wheel 68 adapted to be driven by a second worm wheel 68^a, the latter being actuated by a finger lever 69.

Surrounding sleeve 67 is a second sleeve 70 having a flanged collar 71 pinned thereto near its end, just beyond the frame 1. The sleeve 70 is formed with two slots 90 each representing a quarter of the outer area and arranged at suitable points on opposite sides of the sleeve. Two sections or inserts 91 corresponding in contour to the curved slots are provided and are of slightly less length than the slots 90. The inserts 91 have their outer ends flush with the flanged collar 71 but are cut off at their inner ends to allow free movement of sleeve 70 back and forth. An operating segment similar to the one shown in Fig. 8 only with a round hole fits over sleeve 70 and is fastened by screws extending through the sections 91 into the inner sleeve 67, just inside of the frame 1 at 83. The inner end of sleeve 70 has loosely carried on it a flange 72 fitted between a fixed collar 80 and a threaded nut 81. Extensions on the flange 72 carry small blocks 72^a provided with rollers 73 adapted to co-operate with the double cam surfaces of a pair of fingers 74, horizontally disposed in openings in the flange end extensions 72. By this construction the flanged extensions 72 are swiveled on the sleeve 70, which permits of independent rotary movement of the member 72 when the curved segment is operated.

Wheel 66 is provided with an index finger 75 registering with a suitable curved line gage 76 carried on the frame 1'. By pushing the finger wheel 66 inwardly and turning the index pointer 75 in relation to the gage 76 the same result exactly is obtained as is accomplished by the principal form by the manipulation and adjustment of knurled wheel 6. Movement of the finger lever 69 outwardly in the direction of the arrow effects a partial rotation of the sleeve 67, and the resultant sequence of operations corresponding to a partial rotation of finger

wheel 18 in the form shown in Figs. 1 to 7 respectively.

The sleeve 70 is capable of sliding on the inner sleeve 67 and is moved by means of a pivoted finger piece 77, one end of which 78 engages the grooved end 71. When the finger piece 77 is actuated so as to move the sleeve 70 to the right, the rollers 73 move down one of the cam surfaces of the fingers' ends 74, thereby releasing the clamping action of the fingers' ends 74, so as to place the parts in the same "neutral" position, previously referred to in order that the platen roller 'P' can be moved forward or backward independently of the operating finger 69.

I claim as my invention:—

1. The combination with a paper carriage and a rotatable platen, of means for moving said platen circumferentially comprising clutch mechanism inclosed within said platen, connections between said clutch mechanism and the platen adapted to be automatically locked and released, a member movable axially of the platen for adjusting said clutch mechanism and a member capable of rotational movement for actuating said clutch mechanism and rotating the platen.

2. The combination with a paper carriage and a fixed cylindrical bearing carried therein, of a rotatable platen surrounding said bearing, means for moving said platen circumferentially comprising clutch mechanism inclosed within said cylindrical bearing, means for actuating said platen, means for alternately locking and releasing the platen to and from said actuating means, and a member movable axially of the platen for varying the adjustments of said clutch mechanism.

3. The combination with a paper carriage and a rotatable platen, of means for moving said platen circumferentially in one direction for line spacing purposes comprising clutch mechanism inclosed within said platen, a rotatable actuating member for said platen, means associated with said clutch mechanism for automatically successively locking and releasing the platen to and from said actuating means, means for retaining said actuating member in a neutral inoperative position, and means independent of said first mentioned means for moving said platen circumferentially forward or backward when said actuating member is in neutral position.

4. The combination with a paper carriage and a rotatable platen, of line spacing mechanism therefor comprising an indicator fixed to said carriage and adapted to extend partially around the platen in proximity to the paper, clutch mechanism inclosed within said platen, adjusting means for said clutch mechanism including a shaft movable axi-

ally and rotatably in relation to said platen, said shaft extending from one end of the platen and carrying on its free end a pointer adapted to coöperate with said fixed indicator, means for actuating said platen, and means associated with said clutch mechanism for alternately locking and releasing said platen to and from said actuating means.

5. In a typewriting machine, the combination of a platen and line spacing devices for controlling the extent of rotation of the platen, said line spacing devices comprising an indicator in proximity to said platen, clutch mechanism inclosed within said platen, a hand wheel at one end of said platen for adjusting said clutch mechanism in relation to the indicator and a second hand wheel at the other end of the platen for actuating the platen after the clutch mechanism has been set to the desired adjustment.

6. In a typewriting machine, the combination of a platen and line spacing devices for controlling the extent of rotation of the platen, said devices comprising a fixed cylindrical bearing for said platen, clutch mechanism inclosed within said cylindrical bearing, a shaft extending from said clutch mechanism to one end of the platen and provided with a hand wheel, said shaft being capable of axial and rotational movement for the purpose of adjusting said clutch mechanism, a shaft extending from said clutch mechanism to the other end of said platen and provided with a hand wheel, said shaft being capable of limited rotational movement for effecting the line spacing movement of the platen subsequent to the adjustment of said clutch mechanism.

40 7. The combination with a paper carriage, and a rotatable platen, of means for regulating the extent of rotation of the platen, comprising clutch mechanism inclosed with-

in said platen, an axially and rotatably movable member at one end of said platen for 45 adjusting the inner clutch mechanism, and a partially rotatable segment at the opposite end for effecting a rotation of said platen, the extent of rotation being dependent upon the adjustment of the inner clutch mecha- 50 nism.

8. The combination with a paper carriage and a rotatable platen, of means for regulating the extent of rotation of the platen comprising clutch mechanism inclosed within 55 said platen, an actuating member for effecting circumferential movement of the platen, means at one end of the platen for adjusting the inner clutch mechanism and means at the other end of the platen for successively operating the clutch mechanism and effecting a locking relation between the platen and said actuating member.

9. The combination with a paper carriage and a rotatable platen, of means for regulating the extent of rotation of the platen, comprising clutch mechanism inclosed within 65 said platen, means at one end of the platen adapted to be moved axially and rotationally to effect an adjustment of the inner clutch 70 mechanism, and similar means at the other end of said platen adapted to be partially rotated to successively actuate said inner clutch mechanism to move the platen circumferentially to an extent independent 75 upon the previous adjustment of the clutch mechanism and automatically return the several parts to their initial positions, respectively.

In testimony whereof, I affix my signature 80 in presence of two witnesses.

JACOB LEE WALZ.
